UNITED STATES PATENT OFFICE.

FRANK F. GERRY, OF SUDBURY, MASSACHUSETTS.

DESIGN FOR A GAME-BOARD.

SPECIFICATION forming part of Design No. 31,760, dated October 31, 1899.

Application filed October 2, 1899. Serial No. 732,412. Term of patent 7 years.

To all whom it may concern:

Be it known that I, FRANK F. GERRY, a citizen of the United States, residing at Sudbury, in the county of Middlesex and State of Massachusetts, have invented and produced a new and useful Design for a Game-Board, of which the following is a description, reference being had to the accompanying drawing, forming a part thereof.

10 This invention has for its object the production of a novel and attractive configuration for a game-board, the chief feature of novelty residing in a cell-like structure rising above the level of the board or base proper 15 and having a mural aperture, in front of and at a small distance from which rises from the board a wall of about the proportions of the mural aperture, wings being extended outward from the cell on each side of the aperture toward, but not as far as, the wall.

The drawing illustrates in perspective a structure embodying my novel design, the reference-letter A designating the board or base proper, from which rises a rectangular cell B, of reticulated material, having a mural opening b, on each side of which is a wing b', while in front thereof is a wall b².

Having thus fully described my invention, what I claim is—

20 The design for a game-board substantially as shown and described.

In testimony whereof I have signed my name to this specification in the presence of two subscribing witnesses.

FRANK F. GERRY.
